Carlo P. Griffin
ATTORNEY.

UNITED STATES PATENT OFFICE.

ANDREW J. SMITH, OF OAKLAND, CALIFORNIA, ASSIGNOR OF ONE-HALF TO
W. B. COCHRAN, OF SAN FRANCISCO, CALIFORNIA.

OIL-BURNER.

1,285,437.

Specification of Letters Patent. Patented Nov. 19, 1918.

Application filed March 5, 1918. Serial No. 220,644.

To all whom it may concern:

Be it known that I, ANDREW J. SMITH, citizen of the United States, residing at Oakland, in the county of Alameda, State 5 of California, have invented a new and useful Oil-Burner, of which the following is a specification in such full and clear terms as will enable those skilled in the art to construct and use the same.

10 This invention relates to an oil burner especially adapted for use with kitchen stoves although, of course, it may be used in any furnace, or other kind of stoves.

15 An object of the invention is to provide a burner with a considerable length of heating pipes whereby the gas will be delivered to the fire in a perfectly vaporized condition, said heating pipes being filled with a material which is adapted to assist in transferring the heat from the pipes to the oil 20 to be vaporized.

25 Another object of the invention is to produce a burner which is capable of having one or more blazes while heating the oil adequately for either of the blazes should only one be used.

30 Another object of the invention is to produce a series of deflectors to receive the direct flame in order to prevent the heating pipe from becoming too hot and carbonizing the oil.

35 Another object of the invention is to provide a burner with additional deflectors which may be used or not at the will of the person operating the stove, the additional deflectors being for the purpose of directing the flame toward the oven or directing it to heat the top of the stove as 40 may be desired.

45 Another object of the invention is to produce a burner which will give the desired heat for all purposes with the smallest fuel consumption.

50 Another object of the invention is to so construct and locate the heating pipes that the lower pipe assists in protecting the upper heating pipe from the flame thereby increasing the life of the pipes.

55 Other objects of the invention will appear as the description proceeds.

60 An embodiment of the invention is shown in the drawings in which the same reference numeral is applied to the same portion

throughout, but I am aware that there may be modifications thereof.

65 Figure 1 is a perspective view of a portion of a stove illustrating the installation therein of its burner, the burner being shown in perspective and side elevation,

70 Fig. 2 is a cross section of one of the burner pipes showing the wires therein which assist in transferring the heat to the fuel.

75 Fig. 3 is a side elevation of a portion of one of the heating pipes, showing one of the deflectors and a portion of the heating wires.

80 Fig. 4 is a vertical sectional view of a three way valve for supplying one or both of the burners with fuel.

85 In the drawing the numeral 1 indicates the stove which has suitable legs 2 and 3, and suitable lids 4, 5 and 6. The grate bars of the stove may be permitted to remain there- 90 in, and are indicated at 7. This burner has its pipes secured to a plate 8, which plate is of a convenient size to place within any suitable stove, the space around the edges of the plate being packed with asbestos fire 95 clay as indicated at 9 to compel all of the air passing to the burner to pass through the two holes 10 and 11 in the plate 8. The plate 8 has suitable holes at its center to receive two pipes 13 and 14, which pipes may be forced thereinto, and which are bent to produce the horizontally extending members 15, 16 and 17 within the fire box, the pipe 13 being similarly bent to produce the horizontal members 15', 16' and 17' within the 100 fire box.

105 From a point adjacent the top of the plate in each of the pipes 13 and 14, a series of wires 19 filling said pipes extend around through the members 15 and 16 to assist in delivering the heat to the oil being burned whereby the vaporization thereof is accelerated. The oil escapes from the pipes 17 and 17' at small openings 20, 20' over the holes 10 and 11, and immediately over said openings are the deflectors 21 and 22. These deflectors are illustrated in Figs. 2 and 3 and consist of the flat plates 24 with a staple 25 for hanging them on the pipes 16, 16'. The plates 24 are spaced away from the pipes 105 supporting them far enough to prevent the flame from heating said pipes red hot, since

the flame will strike the deflector plates and be thrown to one side or the other as the case may be.

In addition to the deflectors 21, 22, there are two other deflectors 25', 26 on the pipes 16 and 16', which deflectors are ordinarily turned up to the position shown in Fig. 1 and out of use. When it is desired to quickly heat the oven, the deflectors 21 and 22 are pushed out of the way of the direct flame making room for the larger deflectors 25 and 26, which latter are then placed over the flames and tilted to direct the flame in the best direction to heat the oven or the top of the stove quickly. The deflectors 21 and 22 are smaller than the deflectors 25 and 26 and are more suitable for ordinary low fires since they do not obstruct the flame so much as the larger spreaders which are used when a more extended flame is to be directed around the oven and without an increase in the fuel used.

When the oven is to be heated, the deflectors 25, 26 are turned to direct the flame back (Fig. 2) and when the top of the stove is to be heated they are tilted so as to cause the flame to move forwardly, (Fig. 1), and thereby give a better effect on the top of the stove.

In order to make it possible to turn the fire down without altering the burning conditions at each flame, the pipes 27, 28 which are connected to the pipes 13, 14, have a three way valve 29 at their front ends. The valve 29 has a plug 30 with suitable passages to permit the oil to be turned to either or both of the pipes 27, 28, as may be desired, and it is operated by means of the handle 31 on the valve stem 32. Below the three way valve there is a pipe 33 and a needle valve 34 to regulate the quantity of oil supplied to the burner.

In operation, the burner is started by throwing a small piece of newspaper into the fire box under the pipes 15, 16. The heat from the paper is sufficient to cause the generation of gas in the pipes 15 and 16, and as the gas issues from the openings 20 it is completely vaporized and burns substantially without a carbon deposit.

It will be noted that it is essential to properly space the deflectors away from the pipes supporting them so as to leave a considerable air space to prevent the pipes from becoming so hot as to cause a carbon deposit therein.

Having thus described my invention what I claim as new and desire to secure by Letters Patent of the United States is as follows:

1. An oil burner comprising a plate adapted to support a burner within a fire box, a pipe passing through said plate and having a plurality of vertically superposed horizontally extending members, the lower of which has a fuel escape opening, a reversible double deflector carried by one of said members to prevent the flame from striking two of the oil supply members directly, and means to control the fuel supply.

2. An oil burner comprising a plate adapted to support the burner within a firebox, a pipe passing through the plate and having a plurality of vertically superposed horizontally extending members the lower of which has a fuel escape opening, a reversible double deflector to prevent the flame from directly striking two of the horizontally extending members, a heat transfer filling in said pipes and a fuel supply valve.

In testimony whereof I have hereunto set my hand this 25th day of February, A. D. 1918.

A. J. SMITH.
